WHEELED TOY WITH WHEEL-ACTUATED
DEVICESThomas E. Byrnes, Bull Valley Road, Woodstock, Ill.
Filed Feb. 3, 1961, Ser. No. 86,977
1 Claim. (Cl. 46—294)

This invention relates to a toy and more particularly to a movable toy which allows variations in locations of movable parts to entertain the user.

It is common to produce toys for children which may be drawn across the floor by means of a drawstring or the like. Children often become disinterested in such toys since they do not afford any opportunity for change or reconstruction. The toy of this invention is one which may be moved as by a drawstring or the like, and which does provide opportunities for reconstruction and change in its outer appearance.

The advantages of the toy of this invention are provided by the use of a plurality of rollers or the like, which may be inserted at random fashion, all of the rollers being movable regardless of their position on movement of the toy.

It is therefore an object of this invention to provide a toy such as described.

It is another object of this invention to provide such a toy wherein the rollers are transparent and may contain additional objects such as figures and the like, which will also move on movement of the toy.

It is still another object of this invention to provide a toy which comprises a frame, a plurality of frame supporting rollers adapted to provide rolling support for the frame as it moves upon the floor, means in the frame for receiving and retaining additional rollers at random positions, and at least one additional roller adapted to be positioned in the means in said random fashion so that frictional driving contact is maintained between the additional roller and at least one of the supporting rollers whereby said additional rollers are rotated upon movement of the frame.

Other objects and advantages of this invention will become apparent from the specification taken together with the following drawings.

Of the drawings:

FIGURE 1 is a perspective view of the embodiment of the toy of this invention;

FIGURE 2 is a side elevational view of the toy shown in FIGURE 1;

FIGURES 3 and 4 are end and top views respectively, of the toy of FIGURE 2;

FIGURE 5 is a sectional view of a roller; and

FIGURES 6 through 8 and 10 are side elevational views of other embodiments of the toy of this invention, FIGURE 9 being an end view of the embodiment of FIGURE 8.

Turning now to the drawings, FIGURE 1 shows one embodiment of the toy 10 of this invention. This embodiment includes a frame 11 which is supported for motion on a plurality of rollers 12 located near the base 11a of the frame. The rollers 12 include a pair of spheres 13 joined by an axle 14. The axle 14 passes through the base of the frame 11a so that the rollers 12 are permanently positioned in the base of the frame. These rollers 12 allow the frame 11 to roll when pulled by the drawstring 15 which is attached to an eye 16 screwed into the frame.

The frame 11 includes a plurality of slots 17 through 23. The slots are substantially similar except that slots 17, 18, 22 and 23 are shorter than slots 19 through 21. Slot 17 has side walls 17a and 17b and a bottom wall 17c as do the other slots.

2

A plurality of additional rollers 24 are designed to be inserted into the slots just described. Each of these rollers also includes a pair of spheres 25 and an axle 26. The spheres 25 may be made of wood or may be hollow and made of a transparent plastic material such as shown in FIGURE 5. In this case, the spheres can contain additional objects 26 which may be figures and the like. Other shaped rollers may be used since it is only necessary that the spheres 25 have a rollable surface such as at 25a which will contact an adjacent sphere.

As can be seen in FIGURE 1, the slots 17 through 23 are designed to receive and retain a plurality of the rollers 24. In FIGURE 1, the slots are actually all full of rollers, the slots receiving the axle 26 and thereby holding the rollers in place. In this condition it can be seen that each sphere 25 contacts at least one of the other spheres in the rollers 24 and that the bottom row of rollers 24 designated at A, contacts the rollers 12. Because of this, when the toy is pulled across the floor, rolling motion will be imparted from the rollers 12 to the rollers 24 so that all of the rollers will move in one direction or another on motion of the toy. However, it is not necessary to completely fill the slots with rollers 24. As can be seen in FIGURE 2, the rollers can be located in a random fashion. Thus in FIGURE 2, there is no roller in the slot 17 or the slot 21, yet because all the remaining rollers contact at least one other roller and because the bottom row still contacts the rollers 12, motion will still be imparted to the inserted rollers 24. This allows the user of the toy to locate the rollers in any fashion desirable and still obtain motion of the rollers.

FIGURES 6 through 8 and 10 show other embodiments of the frame member 11 all including, however, the same principle. Thus in FIGURE 6 a different shape frame 27 includes two pairs of rollers 12 and an additional sphere 28. In FIGURE 7, the frame 29 is in the form of a toy train including a toy caboose 30, a toy car 31, and a toy engine 32, each of which are provided with slots 30a, 30b, 31a, 31b, and 31c and 32a. Rollers 24 are designed to be inserted into these slots.

In FIGURES 8 and 9, the frame 33 has a shape of a clown 33 with the clown's hand defining a slot 33b designed to receive a roller 24.

FIGURE 10 shows a frame 34 which is in the shape of an elephant, the elephant's tail 34a defining a slot 34b and the elephant's trunk 34c defining a slot 34d. Each of these slots is designed to receive a roller 24.

All of the constructions of FIGURES 6 through 8 and 10 provide the same opportunities for relocation of rollers as the construction of FIGURE 1 so that the user may change the toy as he desires.

Having thus described my invention as related to the embodiments shown in the accompanying drawings, it is my intention that the invention be not limited by any of the details of description unless otherwise specified, but rather be construed broadly within its spirit and scope as set out in the accompanying claim.

I claim:

60. A movable toy, comprising: an upstanding frame having a thickness less than its height; a plurality of pairs of frame supporting rollers substantially permanently mounted for rotation on said frame at spaced positions adjacent the bottom of said frame with the rollers of said pairs being on the opposite sides of said frame, said rollers being adapted to provide rolling support for said frame; a plurality of substantially vertically extending transverse slots in said frame, said slots being open on the top surface of said frame for receiving and retaining additional rollers in random positions superposed in relationship to said permanently mounted rollers, some of said slots being deeper than others of said slots so that

the bottoms of some of said slots are adjacent the location of said supporting rollers; and a plurality of additional rollers, each having rollable surfaces and a shaft therebetween, said shafts being adapted to be positioned in said slots in random fashion with the rollable surfaces of said rollers positioned outside of either side of said frame in peripheral engagement with at least one of said supporting rollers and the rollable surfaces of any additional rollers positioned thereabove in the same or adjacent slots, so that rotation of said supporting rollers upon movement of said frame will cause rotation of said additional rollers.
